UNITED STATES PATENT OFFICE

HARRY VOGT AND JOHN HECK, OF BROOKLYN, NEW YORK

DEVICE FOR WINDING, COMBING, STRETCHING, AND TYING HAIR IN THE MAKING
OF PERMANENT WAVES

Application filed September 22, 1930. Serial No. 483,527.

Our invention relates to an auxiliary apparatus to be used in the production of permanent hair waves, and it is the principal object of our invention to provide an apparatus which pleats the hair in perfect smooth and flat condition, and one which winds, combs, stretches and ties the hair in one operation.

Another object of our invention is the provision of a device of this character which is comparatively simple and inexpensive, yet durable and highly efficient in operation.

Still another object of our invention is the provision of an apparatus of this type in which a padded roller engages the hair between itself and a suitable table guiding the hair to stretch the same to allow a winding about a stick while a spring controlled lever engages the strand of the hair to keep the same at all times smooth and flat on the curling stick.

A further object of our device is the provision of an apparatus allowing the ready introduction of a paper strip, metal reinforced or not, between the hair strands.

A still further object of our invention is the provision of an apparatus of this character equipped with two arms pivotally attached at one end while an operating lever allows a spreading apart of the arms against the action of a leaf spring tending to close the arms to clamp the hair between their other ends.

These and other objects and advantages of our invention will become more fully known as the description thereof proceeds and will then be specifically defined in the appended claims.

In the accompanying drawings forming a material part of this disclosure:

Fig. 1 is a plan view of our hair pleater constructed according to our invention.

Fig. 2 is a side elevation thereof with the comb omitted.

Fig. 3 is a perspective detail view of the comb and hair guide.

Fig. 4 is a fragmentary side elevation illustrating the initial step in the formation of a wave.

Fig. 5 is a section on line 5—5 of Figure 1.

Fig. 6 is a section on line 6—6 of Figure 2.

Fig. 7 is a detail view of the curler rod 55 and hair wave thereon.

Fig. 8 shows in top elevation a reinforced wave inset.

As illustrated, our novel and improved hair winding, combing, stretching and tying device according to our invention consists of a block 10 having a bore in the direction of its longitudinal axis for the reception of the rod 11 about which the hair is to be wound, and which is held within the block 60 by means of a leaf spring 12 pressing against said rod through an opening 13 in the top of body 10 with one of its ends, while its other end is attached to block 10 by means of the screws 14 or the like. 70

One end of the rod 11 is preferably forked, as at 15 to allow a tying of the end of the hair formed into a wave, while the other end is reduced, as at 16.

To the lower face of body 10 an arm 17 75 of a bracket is attached, to the inner end of which is pivotally secured, as at 18, the other arm 19 of said bracket, and a semi-circular spring band 20 engages with its ends in recesses formed in the arms near 80 their outer ends for limiting the outward movement of said arms.

The arm 17 has its inner end angularly bent, and supporting a table or guide 21 for the hair while a funnel 22 having a wide lower mouth and a comparatively small upper mouth is integrally made with the table and arm 17 and arranged somewhat inclined thereto, for the purpose of allowing the introduction of a ribbon or band 90 23, which is preferably provided with metal reinforcements 24, as shown in Figure 8, to be inserted between the hair. A bar 25 is attached to one side of the guide table 21 and carries at its other end a comb 26. 95

The arm 19 has its inner end curved and formed into a rubber mounted roller 27, and a curved arm 28 attached to arm 19 carries a holder plate 29. Arm 17 and 19 are spread apart by means of a lever 30 pivoted inter- 100

mediate its forked ends to arm 17 and having near its outer forked end a pin 31 bearing against the edge of arm 19 so as to spread the arms 17, 19, apart if lever 30 is turned about its pivot 32 by means of the handle 33.

A looped spring 34 has one of its ends secured to the upper face of block 10 while its other end bears against the lower face 10 of a lever 35 pivoted intermediate its ends, as at 36 to a bracket on body 10 and bearing with its inner end 37 against the hair curl 38 as shown in Figure 1.

The device operates as follows:

15 A supply of hair 39 (Fig. 4) is guided through comb 26 over the outer face of funnel 22, and table 21, and if then the arms, which were spread apart before, are carried together by means of the proper operation 20 of lever 30 and its handle 33, the roller 27 will firmly but movably guide the hair and flatten the same so that it can now be tightly wound about rod 11 with the paper 23 wound in between so as to produce a perfectly flat, smooth wave, the end of which is secured by means of a lever 40 between the prongs of the fork 15.

The end 37 of lever 35 keeps the hair smooth. The hair 39 passing through comb 26 is thereby combed and is then stretched between table 21 and roller 27 while plate 29 prevents its leaving the comb during the operation of the apparatus.

35 It will be understood that we have shown and described the preferred form of our device only as one example of the many possible ways to practically construct the same, and that we may make such changes in the general arrangement of and in the construction 40 of its minor details as come within the scope of the appended claims without departure from the spirit of our invention and the principles involved.

45 Having thus described our invention, what we claim as new and desire to secure by Letters Patent is:

1. A device for winding, combing, stretching, and tying the hair comprising a holder block for the reception of a stick or a pin 50 upon which the hair is to be wound, a spring for holding said pin in said block, a table and a roller for clamping the hair between them, a means for guiding said roller against said table with the hair between both, a comb, means for attaching said comb to the table, a means for holding and guiding the hair passing through the comb, a spring controlled means for holding the hair flat and smooth upon said stick, a means for guiding paper between the hair 60 during its winding upon said stick, and a means for tying the end of the hair to said stick.

2. In a device of the class described, a 65 clamping means for the hair, comprising a

two armed lever, both arms of said lever pivotally connected at one of their ends, and having recesses or notches formed in their ends, a flat open spring having its ends engaged in the recesses of the arms to press 70 the arms together and for limiting their outward movement, a table on one arm, and a roller on the other arm, and an operating lever pivoted to one of said arms and having a forked end, a pin between the prongs 75 of the fork to engage the other arm for allowing a spreading of the same to allow the placing of the hair between said table, and roller to loosely clamp the same therebetween.

3. In a device of the class described, a holder for a stick upon which the hair is to be wound, and a spring controlled lever pivoted intermediate its ends to a bracket on said holder, one end of said lever engaging 80 the hair wound or curled about said stick to keep it flat and smooth thereon.

4. In a device of the class described, a table for guiding the hair, a roller for clamping said hair to said table, a two-armed operating lever clamping said roller against said table, a comb, means for connecting said comb and table, a plate for holding said hair during its passage through the comb, means connecting said plate to one arm of said lever, and means for feeding paper between 90 the hair during the waving operation.

Signed at New York, in the county of New York, and State of New York, this 16th day of September, A. D. 1930.

HARRY VOGT.
JOHN HECK.
